UNITED STATES PATENT OFFICE.

JOHN G. VAUGHAN, OF MIDDLEBOROUGH, MASSACHUSETTS.

CONSTRUCTION OF CHIMNEYS.

SPECIFICATION forming part of Letters Patent No. 341,362, dated May 4, 1886.

Application filed November 23, 1885. Serial No. 183,727. (No model.)

To all whom it may concern:

Be it known that I, JOHN G. VAUGHAN, of Middleborough, in the county of Plymouth and State of Massachusetts, have invented 5 certain new and useful Improvements in Construction of Chimneys, of which the following is a full, clear, and exact description.

This improved chimney is composed of inner and outer pipes made of clay or other 10 suitable plastic material, molded and baked, and preferably glazed on their exposed surface, and of an intermediate filling made of lime mortar or other suitable plastic material, and having a ventilating flue or flues formed 15 in the same, all substantially as hereinafter described.

In the drawings, forming a part of this specification, Figure 1 is a central sectional elevation of my improved chimney. Fig. 2 is a 20 horizontal section on line x x , Fig. 1.

In the drawings, A is an inner, and B is an outer, pipe, and C is an intermediate filling between them.

D is the chimney-passage, and E E are series of ventilating-passages through the filling C, and extending vertically, the whole 25 making the improved chimney of this invention, and as hereinafter described.

The inner and outer pipes, A B, are made 30 of clay or other suitable plastic material, molded and baked, and preferably glazed on their exposed surfaces a b on the inside and outside of the chimney. These pipes are in separate sections or lengths, placed end to end, 35 and jointed at their ends, preferably with inclining faces d , leading downward to the exposed surfaces a b of the pipes, and either with or without a flange, as at f , Fig. 1.

As the chimney is constructed of the pipe- 40 sections placed one upon the other end to end, as above stated, the space between the inner and outer pipes is filled in with lime mortar or other suitable plastic material, so as to make the filling C, and as so filled in iron 45 core-bars are used, about which to mold the filling material to produce thereby the ventilating-flues E, the core-bars being removed and replaced from time to time as the building up of the chimney goes on. These flues 50 E extend from the bottom to the top of the chimney through the filling C, and they may be of any desired number. These ventilating-

passages are open at their lower and upper ends, and the chimney, when completed, is to be finished at its top in any suitable manner. 55

The ventilating-flues allow a circulation of air through them, thus acting to protect the building from the heat of the chimney-flue, also to keep the chimney dry and in better condition for use at all times. 60

H is a thimble passing from the outside to the inside of the chimney to receive a stove-pipe or to make other connection with a fire-grate, &c. This thimble is made of cast metal, and it has a passage, g, in its thickness and 65 around its opening J, to connect at either end the ventilating-passage, which it may intersect, by its insertion in the construction of the chimney.

The downward inclined jointing of the pipe- 70 section, and in the direction stated, prevents moisture working from the inside and the outside of the chimney into the filling.

Having thus described my invention, I claim— 75

1. A chimney composed of separately made outer and inner pipes, A B, of clay or other similar material, molded and baked, and each pipe in sections suitably jointed at their ends, in combination with a filling, C, of lime mortar or other similar plastic material, placed 80 and molded in the space between them, and enclosing a vertical ventilating passage or passages, E, molded therein as the chimney is built, and open at top and bottom, substantially as 85 described, for the purpose specified.

2. A chimney composed of inner and outer pipes, A B, made in sections, and an intermediate filling, C, having ventilating passage or passages in and through it, and a thimble, 90 H, to connect the chimney-passage with a stove, &c., which has a surrounding independent passage which connects the ventilating-passage above and below said thimble, substantially as described, for the purpose speci- 95 fied.

In testimony whereof I have hereunto set my hand in the presence of two subscribing witnesses.

JOHN G. VAUGHAN.
